UNITED STATES PATENT OFFICE.

CESARE LAURENTI, OF SPEZIA, ITALY, ASSIGNOR TO SOCIETÀ ANONIMA FIAT-SAN GIORGIO, OF SPEZIA, ITALY.

TORPEDO-TUBE.

1,209,729.

Specification of Letters Patent. Patented Dec. 26, 1916.

Application filed January 13, 1916. Serial No. 71,977.

To all whom it may concern:

Be it known that I, CESARE LAURENTI, of Spezia, Italy, a subject of the King of Italy, have invented certain new and useful Improvements in Torpedo-Tubes, of which the following is a full, clear, and exact specification.

The present invention relates to an improvement in torpedo tubes, the purpose of 10 the invention being to render the proceedings incident to the launching of torpedoes more rapid by providing for the control of the directing mechanism of the torpedo from the exterior of the tube, thereby avoiding 15 the necessity of withdrawing the torpedo from the tube for setting, or changing the setting of its directing mechanism.

A further purpose of the invention is to provide means enabling the same tube to be 20 used for torpedoes of different lengths. The mechanism provides for the operation of the mechanism for operating the directing mechanism of the torpedo, upon torpedoes of different lengths.

25 Other features of the invention will be hereinafter set forth.

An embodiment of the invention is illustrated in the accompanying drawings.

Figure 1 is part of a cross-section of a 30 torpedo firing tube B at the location of the small shaft 5 on the torpedo A, the rotation of which shaft 5 regulates the angle of the gyroscope of the torpedo. Fig. 2 is a vertical sectional view of the mechanism shown 35 in Fig. 1, on the line II-II in Fig. 1. Fig. 3 is a horizontal sectional view (with parts in elevation) on the line III-III. Fig. 2. Fig. 4 is a view showing details of the coupling of the rod 2 with other parts of the 40 mechanism. Figs. 5 and 6 are perspective views of parts of the coupling shown in Figs. 2 and 4. Fig. 7 is a horizontal sectional view of the adjustable detent mechanism for effecting the proper positioning of torpedoes 45 (for example, torpedoes of different length) in the launching tube with respect to the gyroscope setting mechanism. Fig. 8 is a vertical sectional view on the line VIII-VIII. Fig. 7. Fig. 9 is a transverse sectional view on the line IX-IX. Fig. 7.

In said drawings, letter A designates a 50 torpedo having a means a for operating the directing mechanism of the torpedo, and B designates a torpedo tube. The torpedo tube 55 is provided with mechanism S for operating

the operating mechanism a of the torpedo, which operates the torpedo directing mechanism. The torpedo tube B is also preferably provided with an adjustable detent mechanism T (Figs. 7 to 9) whereby torpedoes of different length may be located in the torpedo tube in proper position to be operated upon by the mechanism S for operating the directing mechanism of the 60 torpedo.

The mechanism S comprises a key 4 which is adapted to coact with the squared end 8 of the rod 5 of the torpedo directing mechanism. As the rod 5 is usually located on a tapered portion of the torpedo and as the 70 torpedo tube is usually cylindrical throughout, there is a space between the interior wall of the torpedo tube and the end of rod 5. Means are provided for moving the key 4 into and out of engagement with the end 75 of shaft 5. This means preferably comprises a rod 2 (provided with a handle 3) having a sliding movement and adapted to operate a crank arm 10-11 which raises and lowers a vertically sliding shaft 9, to the 80 lower end of which the key 4 is connected. The key 4 is preferably formed in two pieces and united to the vertical shaft 9 by means of a dove-tail joint, the pieces being held in place by means of a circular spring 4a. The 85 shaft 9 carrying the key 4 is also capable of being rotated by a rotary movement of the rod 2 and handle 3, the rotation of the shaft 9 being conveniently effected by means of a worm wheel 9a meshing with a worm wheel 9b splined upon the shaft 9. The worm 9a is fixed upon an extension 2a of a sleeve 2b surrounding the rod 2. The connection between the rod 2 and the sleeve 2b, whereby 90 the rod 2 and sleeve 2b turn together, is preferably made by means of lugs 6, 6, on the rod 2, and grooves or recesses 6a, 6a in a part fixed to the sleeve 2b, as will be herein-after explained. The connection between 95 the rod 2 and the crank arm 10-11, whereby the crank arm 10-11 is rocked to raise and lower the shaft 9 carrying the key 4, preferably comprises a pair of collars 2c, loose on the rod 2. The collars 2c have projecting lugs 2d thereon adapted to project through a slot 2e in the sleeve 2b. On turning the rod 2, rod 2 turns in the collars 2c, 2c without turning the collars. Between the lugs 2d and surrounding the sleeve 2b, there 100 is arranged a ring 2f having studs 2g thereon

110

adapted to engage between the forked ends 11^a of the arm 11 of the crank arm 10—11. By this arrangement of the ring 2^c and shouldered collars 2^c, the rod 2, by a sliding 5 movement thereof, rocks the crank arm 10—11. The arrangement also permits of the rod 2 and sleeve 2^b being turned while the connection is maintained with the crank arm 10—11.

- 10 In order that the socket in the key 4 may register with the squared end 8 of the shaft 5 of the mechanism *a* of the torpedo, the rod 2 is provided with suitable data for indicating a precise position corresponding to registry of the said parts. This data may be one or more lines L upon the rod 2. When the lines L are in a horizontal plane or are opposite a suitable index, it is known that the key 4 is in a position to engage the end 8 of the shaft 5 when the key is lowered. 15 When the rod 2 is in position to bring the key 4 in position to register with the end 8 of the shaft 5, as just explained, the handle 3 may be pulled, sliding the rod 2, rocking 20 the crank arm 10—11, and lowering the key 4 into engagement with the squared end 8 of the shaft 5. A datum mark M on the rod 2 is seen, which indicates that the key 4 is in complete engagement with the squared 25 end 8. This sliding movement of the rod 2 brings a pair of lugs 6 into diametrically opposite slots 6^a in a collar 1. If the lugs 6 on the rod 2 are in registry with the slots 6^a the rod 2 may be pulled farther (a datum 30 line N on the rod 2 indicating the limit of the further movement), and the shaft 5 depressed, the depression of the shaft 5 releasing it and permitting of turning thereof by the key 4 to permit of the setting of the 35 directing mechanism of the torpedo. The key 4 is turned by turning the handle 3 on the rod 2, and the extent of rotary movement of the handle and key (and hence the extent of movement of the torpedo directing mechanism) may be ascertained by means of a 40 pointer 7 carried by a fixed part of the mechanism and suitable calibrations upon the face 7^a of the sleeve 2^b which turns with the rod 2.
- 45 It is not possible to rotate the key 4 to turn the torpedo governing mechanism until the key 4 is entirely in engagement with the end 8 of the shaft 5. This complete engagement, as explained, is indicated by the 50 datum lines M and N, and the connection between the rod 2 and the sleeve 2^b is only effected when the lugs 6 engage the slots 6^a in collar 1 attached to the sleeve 2^b, and these lugs 6 only enter the slots 6^a after the 55 datum lines M, N appear, and consequently 60 after the key 4 is in complete engagement with the end 8 of the shaft 5 of the mechanism *a* of the torpedo.

The detent mechanism T (see Figs. 7, 8 and 9) will now be described. This mecha-

nism permits of the stopping or positioning of torpedoes of different length in the torpedo tube B, to permit of the mechanism *a* of the torpedo to be in proper position axially of the tube to be engaged by the key 4 of the mechanism S. The mechanism T comprises a casing Q housing the detent F, which projects into a slot F' in the torpedo tube, and the torpedo tube is provided with another slot F² within the casing Q of such length as to permit the detent F at the extremities of the slot F² to engage the stops on torpedoes of the maximum and minimum length which are intended to be used in the tube B. The stop F is preferably carried in a slide F⁴, and the position of the stop F in the slot F' may be adjusted by means of a rod P (having an axial and a sliding movement), a gear wheel p fitted upon a polygonal portion p' of the shaft P, and intermediate pinion p², a threaded gear wheel p³ and a threaded shaft C attached to the slide F⁴ carrying the stop F. By turning the rod P the threaded rod C is caused to move back and forth in the casing, carrying with it the slide F⁴ and stop F.

The stop F is adapted to be moved out of engagement with a stop on the torpedo, so as to release the torpedo in firing. To this end the stop F is provided with a stem f having a stud f² thereon adapted to fit in a groove f³ in a gear wheel f⁴ meshing with an intermediate gear f⁵ which meshes with a rack f⁶ carried by a sleeve G upon the rod P. By a sliding movement of the rod P the sleeve G is carried with it, causing the rack f⁶ to rotate the intermediate gear f⁵ and the gear f⁴, the groove f³ of the gear f⁴ engaging with the stud f² on the stem f of the stop F to raise the stop F (or lower the stop F, as the case may be).

To permit of the adjustment of the slide f⁴ by a turning movement of the rod P without the raising or lowering of the stop F being effected, the sleeve G and rod P are provided with interengaging screw threads. When the rod C is axially moved by a turning movement of the rod P, the sleeve G on the rod P is moved correspondingly. That is, when the rod P is turned the slide F⁴ and the sleeve G move in the same direction and to the same extent. Consequently, the slide F⁴ carrying the stop F may be adjusted without disconnection of, or interference by, the parts which act to operate the stop F to release the torpedo. The stop F may be adjusted by a turning movement of the rod P, and when it is desired to release the torpedo the rod P is pulled or slid, carrying with it the sleeve G having the rack f⁶ thereon and raising the stop F out of the path of the stop on the torpedo, as hereinbefore explained.

The inventive ideas herein disclosed may receive other mechanical expressions than

those herein specifically illustrated and described.

I claim as my invention:—

- 5 1. Apparatus for launching torpedoes, comprising a tube, and a stop adjustable longitudinally of the tube for coöperating with means on the torpedoes to position torpedoes of different dimensions in the tube.
- 10 2. Apparatus for launching torpedoes, comprising a tube, and a stop adjustable longitudinally of the tube for coöperating with means on the torpedoes to position torpedoes of different dimensions in the tube, and 15 means for displacing said stop in launching the torpedo.
- 15 3. Apparatus for launching torpedoes, comprising a tube, means for adjusting the gyroscope setting mechanism of the torpedo, and a stop adjustable longitudinally of the tube for coöperating with means on the torpedoes to position torpedoes of different dimensions in the tube with respect to said gyroscope setting adjusting means.
- 20 4. Apparatus for launching torpedoes, comprising a tube, and a stop adjustable longitudinally of the tube for coöperating with means on the torpedoes to position torpedoes of different dimensions in the tube, means 25 for adjusting said stop, and means for displacing said stop to release the torpedo, said displacing means having a part having a compensatory movement when said stop is adjusted.
- 25 5. Apparatus for launching torpedoes, comprising a tube, a stop for coöperating with means on the torpedoes to position torpedoes therein, and means for adjusting said stop longitudinally of the tube, said 30 means comprising an operating rod having a rotary and a sliding movement, a slide carrying said stop, and means operated by a rotary movement of the operating rod for displacing said slide, and means for displacing said stop to release the torpedo, said 35 means comprising a part displaceable with said slide and adapted when operated by a sliding movement of said operating rod to displace said stop.
- 35 6. Apparatus for launching torpedoes, comprising a tube, a stop for coöperating with means on the torpedoes to position torpedoes therein, and means for adjusting said stop longitudinally of the tube, said 40 means comprising an operating rod having a rotary and a sliding movement; a slide carrying said stop, a rotary shaft having a threaded connection with said slide, gears between said operating rod and said rotary shaft for turning said rotary shaft by a turning movement of the operating rod, and means for displacing said stop to release the torpedo, said means comprising a part 45 having a threaded connection with said operating rod and adapted to be correspond-

ingly moved when said slide is moved, and means between said part and stop adapted to be operated by a sliding movement of said operating rod and part to displace said stop.

7. Apparatus for launching torpedoes, comprising a tube, a stop for coöperating with means on the torpedoes to position torpedoes therein, and means for adjusting said stop longitudinally of the tube, 75 said means comprising an operating rod having a rotary and a sliding movement; a slide carrying said stop, a rotary shaft having a threaded connection with said slide, gears between said operating rod and said rotary shaft for turning said rotary shaft by a turning movement of the operating rod, and means for displacing said stop to release the torpedo, said means comprising a part having a threaded connection 80 with said operating rod and adapted to be correspondingly moved when said slide is moved, means on the slide for displacing said stop, said last named means being adapted to be operated to displace the stop 85 for releasing the torpedo.

8. Apparatus for launching torpedoes, comprising a tube and means for adjusting the gyroscope setting mechanism of the torpedo, said means comprising a part movable into and out of engagement with said gyroscope setting mechanism, and means for moving said part into and out of the aforesaid engagement, means for turning said part, and means for rendering said 100 means for turning automatically operative after the movement of said part into engagement with the gyroscope setting mechanism, said turning means being automatically inoperative until movement of said part into 105 engagement with the gyroscope setting mechanism.

9. Apparatus for launching torpedoes, comprising a tube and means for adjusting the gyroscope setting mechanism of the torpedo, said means comprising a part movable into and out of engagement with said gyroscope setting mechanism, an operating rod for moving said part into and out of the aforesaid engagement, and means for 110 turning said part to operate the setting mechanism, said means being operable by a turning movement of said operating rod.

10. Apparatus for launching torpedoes, comprising a tube and means for adjusting the gyroscope setting mechanism of the torpedo, said means comprising a part movable into and out of engagement with said gyroscope setting mechanism, an operating rod for moving said part into and out of the 120 aforesaid engagement, and means for turning said part to operate the setting mechanism, said means being operable by a turning movement of said operating rod, and means establishing operable connection with 125

the operating rod after said part is moved into engagement with the gyroscope setting mechanism.

11. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, and means for turning said part when said operating rod is turned.
12. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, said means comprising a crank-arm, and means for turning said part when said operating rod is turned.

13. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, and means for turning said part when said operating rod is turned, said means comprising a sleeve, and a coupling for connecting said sleeve and operating rod.

14. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, said means comprising a crank-arm, and means for turning said part when said operating rod is turned, said means comprising a sleeve, and a coupling for connecting said sleeve and operating rod.

15. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, and means for turning said part when said operating rod is turned, said means comprising a sleeve, and a coupling for connecting said sleeve and operating rod.

ating rod is turned, said means comprising a sleeve, and a coupling for connecting said sleeve and operating rod, said coupling being coupled after the sliding movement of the rod has effected movement of said part into engagement with the gyroscope setting mechanism.

16. Apparatus for launching torpedoes, comprising a tube, and means for adjusting the gyroscope setting mechanism of the torpedo, said means comprising a part movable into and out of engagement with said gyroscope setting mechanism, an operating rod, and means for turning said part when said operating rod is turned, said means comprising a sleeve, and a coupling for connecting said sleeve and operating rod, said coupling being coupled after the sliding movement of the rod has effected movement of said part into engagement with the gyroscope setting mechanism, and indicia indicating the completion of the sliding movement of said operating rod.

17. Apparatus for launching torpedoes, comprising a tube, and means for adjusting the gyroscope setting mechanism of the torpedo, said means comprising a part movable into and out of engagement with said gyroscope setting mechanism, an operating rod having a sliding and a rotating movement, means moving said part in and out by a sliding movement of said operating rod, and means for turning said part when said operating rod is turned, said means comprising a sleeve, and a coupling for connecting said sleeve and operating rod, and indicia indicating the normal angular position of said operating rod.

18. Apparatus for launching torpedoes, comprising a tube, and means for adjusting the gyroscope setting mechanism of the torpedo, said means comprising a part movable into and out of engagement with said gyroscope setting mechanism, an operating rod, and means for turning said part when said operating rod is turned, said means comprising a sleeve, and a coupling for connecting said sleeve and operating rod, said coupling being coupled after the sliding movement of the rod has effected movement of said part into engagement with the gyroscope setting mechanism, indicia indicating the completion of the sliding movement of said operating rod, and indicia indicating the normal angular position of said operating rod.

In witness whereof, I have hereunto signed my name in the presence of two subscribing witnesses.

ING. CESARE LAURENTI.
